UNITED STATES PATENT OFFICE

100,420

DESIGN FOR A SHOE

Jacob Fishman, Brooklyn, N. Y., assignor to Geo. E. Keith Company, Campello, Mass., a corporation of Massachusetts

Application May 27, 1936, Serial No. 62,863

Term of patent 3½ years

To all whom it may concern:

Be it known that I, Jacob Fishman, a citizen of the United States, residing at Brooklyn, in the county of Kings and State of New York, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side view of the same. The design

of the vamp and quarter is substantially the same on both sides of the shoe.

The essential feature of the invention resides in ornamenting the vamp and the quarter of a shoe with the design shown. As the design is applicable to shoes of various shapes and styles the representation of shoe is merely conventional, for showing an application of the design.

I claim:

The ornamental design for a shoe, as shown and described.

JACOB FISHMAN.
